UNITED STATES PATENT OFFICE.

ARTHUR W. BEAUPRIE, OF ATLANTA, GEORGIA.

TELEGRAPH-SOUNDER.

1,265,589.

Specification of Letters Patent.

Patented May 7, 1918.

Application filed February 12, 1916. Serial No. 77,928.

To all whom it may concern:

Be it known that I, ARTHUR W. BEAUPRIE, a citizen of the United States, residing at Atlanta, in the county of Fulton and State of Georgia, have invented new and useful Improvements in Telegraph-Sounders, of which the following is a specification.

This invention relates to telegraph sounders and has for its primary object to construct a sounder capable of being operated by alternating current.

An object of the invention is to provide a sounder of simple construction capable of being operated by alternating current and in which the parts are so related as to prevent chattering of the armature.

Another object of the invention is to provide a duplex core so arranged that there will be a mutual attraction between the two irrespective of the character of current passing through the solenoid or magnet.

A further object of the invention is the manner of mounting one of the cores so that the action thereof can be accurately regulated.

With these and other objects in view the invention consists in the construction, combination and arrangement of parts as will be hereinafter more fully described, illustrated in the accompanying drawings and pointed out in the claim hereunto appended.

In the drawings:—

Figure 1 is a vertical sectional view of the sounder in normal position.

Fig. 2 is a similar view showing the parts in active position.

Fig. 3 is a top plan view of the sounder.

In the drawings the numeral 1 designates a base of any suitable insulating material having mounted thereon the spool 2 also composed of insulating material. This spool 2 carries the usual winding 3 and this spool 2 has in turn mounted thereon a bracket 4. In counter-distinction to the usual core I provide a duplex core 5 one member 6 of which is mounted for slidable movement while the other member 7 thereof is held fixed by means of a screw 8 pass-

ing upwardly through the base 1 and entering the member 7. The member 6 is provided with a threaded shank 9 passing through the bracket 4 and this threaded shank 9 has mounted thereon a pair of adjusting nuts 10 coöperating with the bracket 4 for limiting the upward movement of the member 6 the second pair of nuts 11 coöperating with the top surface of the bracket for limiting the movement of the member 6 within the spool 2 in a resilient manner. This is readily accomplished by encircling that portion of the shank 9 between the nuts 11 and the bracket 4 with a spring 12.

By constructing a sounder as set forth each time there is a reversal of current the magnetism of the members 6 and 7 will change with the result that there will always be an attraction between the members for causing a telegraphic sound to be given, and this action is accurately regulated by means of the spring and nuts. It is to be understood that the residual magnetism in the members will be great enough to hold the same in contact during the passage from a positive to a negative electrification.

From the foregoing description taken in connection with the accompanying drawings it should be apparent that I have provided a device which is admirably adapted for the purpose for which it is intended, that the device is simple, durable and efficient of construction, and that the device may be manufactured and sold at a comparatively low cost. I also desire it to be understood that I do not desire to be limited to the use of the device in telegraph systems as the same may be as effectively used as a circuit closure for alternating current.

The changes in the form, proportion and minor details of construction may be made within the scope of the claim without departing from the spirit or sacrificing any of the advantages of the invention.

What I claim is:—

A telegraph sounder for use with alternating currents comprising a non-conductive base, a vertical solenoid connected to
